(57) **CLAIM**

The ornamental design for a cleaning robot with rotary mop as shown and described.

DESCRIPTION

Cleaning robot with rotary mop

Reproduction 1.1 is a front view of a cleaning robot with rotary mop, showing our new design;

Reproduction 1.2 is a back view thereof;

Reproduction 1.3 is a left view thereof;

Reproduction 1.4 is a right view thereof;

Reproduction 1.5 is an enlarged view of part A boxed and marked in reproduction 1.4;

Reproduction 1.6 is a top view thereof;

Reproduction 1.7 is a bottom view thereof;

Reproduction 1.8 is a perspective view thereof;

Reproduction 1.9 is an enlarged view of part B boxed and marked in reproduction 1.8;

Reproduction 1.10 is another perspective view thereof;

Reproduction 1.11 is an enlarged view of part C boxed and marked in reproduction 1.10.

The broken lines in the reproductions depict portions of the cleaning robot that form no part of the claimed design, while only the rotary mop of the cleaning robot is claimed.

1 Claim, 7 Drawing Sheets
